UNITED STATES PATENT OFFICE.

GREENLEAF WHITTIER PICKARD, OF AMESBURY, MASSACHUSETTS.

OSCILLATION-RECEIVER.

No. 888,191.

Specification of Letters Patent.

Patented May 19, 1908.

Original application filed March 9, 1907, Serial No. 361,444. Divided and this application filed November 9, 1907.
Serial No. 401,363.

To all whom it may concern:

Be it known that I, GREENLEAF WHITTIER PICKARD, a citizen of the United States of America, and a resident of the town of Amesbury, State of Massachusetts, have invented certain new and useful Improvements in Oscillation-receivers, the principles of which are set forth in the following specification and accompanying drawings, which disclose the form of the invention which I now consider to be the best of the various forms in which these principles may be embodied.

This application is a division of my application Serial Number 361,444, filed March 9,

15 1907. This invention relates to improvements in oscillation receivers, for use in receiving communications transmitted by electromagnetic waves, and for similar uses.

20 The object of the invention is a commercially stable and sensitive device of the kind specified.

25 The invention involves an oscillation receiver having as one member a conductor possessing the property of one of those specified in said original application.

30 Of the drawings, Figure 1 is a vertical section of a complete embodiment of the invention, Fig. 2 is a plan of the same, both figures being on a two to one scale, in respect of a commercial device.

35 In Fig. 1 the two solid conductors appear at A and B. The binding posts for the circuit terminals are shown at E and E', Fig. 2. The permanent leads, A¹, from member A, and B' from member B, lie in the insulating base I, in holes drilled horizontally from the recesses for the heads of screws H and D to the recesses for the heads of the screws of the 40 binding posts. Each of the conductors A and B may be any suitable conductor of electricity, provided that at least one of them is a solid possessing the property of rectifying electrical oscillations, and the two conductors 45 preferably having a wide difference in specific conductivity. The member A may for example be of brass and the member B a mass of the natural element silicon having extremely low conductivity, provided that the contact

50 surface of the silicon member with which the terminal T J of member A is to engage, or at least a part of that surface, is polished, thereby requiring lower optimum pressure of spring S on member A, and providing a lower 55 resistance at junction T J than when un-

polished, and providing a device which is more useful in circuits of low impedance. The polishing of the operative surface of member B apparently emphasizes the rectification property of the material such that the resultant effective current consists of the oscillations in the direction which is least opposed by the material; as distinguished from the thermo-electric property of the material, the resultant of the action of which is apparently an electromotive force in the other direction. This rectification action is apparently also accentuated by the enormous difference in specific conductivity between the brass member A and member B.

70 The member B is placed in a liquefied mass of fusible metal M in a conducting cup P, so that when the metal M cools and solidifies, the member B will be embedded therein in good conducting relation therewith. The cup P rests on the metallic plate K, held on the base I by the pin N. Hence the cup P may be slid around on K, as desired, to instantly present different parts of its polished surface to the end of member A, that end being electrically small as compared with the other contacts in series.

75 The member A is carried in a sleeve L which is vertically movable in a guide G of a bracket Z secured to base I. The spring S is held in the sleeve L by the cup C, and the spring presses member A down on member B. In use, the telegraph or other operator rapidly moves the sleeve L up and down in the guide G of bracket Z, by downward finger pressure on the cup C, and release of pressure is indicated in the usual telephone connected to posts E and E'. Then the screw is tightened to clamp the sleeve L in this position of maximum sensitiveness at 95 that particular pressure of spring S. Finally the operator moves the cup P around on super-base K until the most sensitive part of the polished surface of member B is reached, as indicated by the telephone response.

I claim:

1. An oscillation receiver, which consists of two electrical conductors, one of which is of brass and the other of which is a mass of silicon having a polished surface.

2. A member of an oscillation receiver, which consists of a mass of the non-metallic chemical element silicon having a polished surface.

3. An oscillation receiver, which consists of two electrical conductors, one of which is a mass of silicon having a polished surface, and the other of which is a conductor of substantially higher specific conductivity.

4. An oscillation receiver, which consists of two electrical conductors, one of which is

a mass of silicon having a polished surface, said conductors operatively having good and small-areaed contact with each other
